Primary Examiner — Brian N Vinson*(74) Attorney, Agent, or Firm* — Bingham Greenebaum Doll LLP(57) **CLAIM**

The ornamental design for a storage caddy, as shown and described.

DESCRIPTION

FIG. 1 is a top, rear, and right side perspective view of a storage caddy showing a first embodiment of my new design; FIG. 2 is a bottom, front, and left side perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a top, rear, and right side perspective view of a second embodiment thereof; and,

FIG. 10 is a top, rear, and left side perspective view of a third embodiment thereof.

The broken-line disclosure in the views is understood to represent portions of the article in which the design is embodied, but which form no part of the claimed design.
